UNITED STATES PATENT OFFICE

THEODORE W. SMITH, OF INDIANAPOLIS, INDIANA, ASSIGNOR TO PETER C. REILLY,
OF INDIANAPOLIS, INDIANA

PROCESS OF IMPREGNATING TIMBER

No Drawing.

Application filed June 21, 1927. Serial No. 200,513.

This invention pertains to an improved process of impregnating fibrous material, and more specifically wood fiber, with a liquid.

More specifically, the invention pertains to the impregnation of pieces of wood, such as poles, with preservative liquids and in such a manner as not to injure or weaken the natural strength of the wood and at the same time to obtain the desired distribution of the preservative throughout the wood, or that part thereof which is required to be treated. The invention is more particularly applicable to the treatment of the butts of poles.

The first requirement in the process of butt-treating poles is to free, as much as possible, the wood fibers in the poles from those elements which interfere with the free and uniform entrance of the preservative liquid into the cavities of the wood structure 20 of the poles.

The principal obstructions necessary to be removed from the cavities of the wood are two, air and moisture. These I remove by the proper application of heat, as will be later 25 described.

An element of obstruction to the exit of moisture and air is introduced into the fibers of the poles, under ordinary practice, whenever the poles are dipped into a liquid, the 30 temperature of which is not sufficient to cause the air in the cavities in the wood to expand quickly and with sufficient force to prevent the absorption of any appreciable amount of the preservative liquid, which, if absorbed, 35 will offer considerable interference to the expulsion of air and moisture from the wood.

In order to prevent initial absorption of the preservative liquid at the beginning of the treating process, which would materially 40 interfere with the expulsion of air and gases from the fibers of wood when the poles are introduced into the liquid preservative, the liquid is heated so as to cause a rapid expansion of the air and also initial vaporization 45 of moisture in the poles, thus preventing absorption of the preservative liquid at this time.

I have found that when the preservative liquid is brought to a temperature of about 50 that of boiling water (100° C.- 212° F.) and

the poles are introduced slowly into the preservative liquid, and at the same time the temperature of the preservative liquid is gradually increased up to about 110° C. to 115° C. (230° F. to 240° F.) that the desired 55 conditions are obtained for favorable expulsion of air and moisture from the wood, for the reason that the hot preservative fluid imparts sufficient heat to the vapors and gases in the wood to create an expansive force 60 greater than the upward pressure (buoyancy) of the preservative liquid against the butts of the poles. On account of these unbalanced forces, there will be an uninterrupted 65 expulsion of gases from the beginning of the treating process to the time the expansive force of the gases in the wood equals the buoyant force of the preservative liquid against the butts of the poles which marks 70 the limit of the rarefaction of the gases at that temperature.

What I have found to be the best practice for keeping the preservative at approximately the desired temperature from the beginning 75 of the operation is to place the poles in a suitable treating tank, of which the bottom and about four feet up the sides are fitted with steam coils, and three or four inches above the bottom coils is placed a perforate platform on which the butts of the poles rest. 80 The preserving liquid is admitted at the bottom of the tank and in passing over the hot coils it is kept at uniformly high temperature around the butts of the poles although the preservative may become slightly cooled 85 as it rises and comes in contact with the cool surface of the poles. Very shortly after the preservative liquid has been added to the proper depth in the tank it is only a matter of a few minutes till all of the preservative 90 has reached a uniform temperature throughout. On the other hand if the poles are plunged rapidly into the hot preservative fluid, heat is not imparted rapidly enough to the gases in the wood to create an expansive 95 force equal to the upward pressure (buoyancy) of the preservative liquid against the butts of the poles, therefore some of the liquid will be forced into the cavities of the wood at the beginning of the operation. This initial 100

obstruction to the liberation of the gases is so strong that it becomes impracticable to increase the heat to a temperature sufficiently high to force this liquid out of the cavities of the wood, which condition hinders the proper 5 rarefaction of the vapors and gases in the wood and thus prevents a uniform distribution of the preservative liquid through the wood. It is this initial absorption of the 10 preservative liquid that has made butt-pole treating methods so unsatisfactory.

That little or no absorption may take place during the time of expelling the air and moisture, I have found that it is necessary 15 to keep the temperature of the preservative liquid in a state of slightly rising temperature from the time the poles are immersed in the liquid until the moisture and air have been expelled. When the liquid has 20 reached a temperature sufficiently high to expel the gases to the desired amount, the temperature can be held at this point, without danger of absorption of the preservative that would interfere with the final expulsion of air 25 and moisture, the temperatures ranging from about 212° F. to 240° F. (or 100° C. to 115° C.) during the process of expelling or removal of the air and moisture from the timber.

30 In order to obtain the necessary space in the fiber of the poles to effect the desired depth and length of impregnation of the wood, I immerse the poles to a greater depth than that to which the poles are to be treated 35 or impregnated. I do this for the purpose of gaining additional voided space within and throughout the pores of the wood and thereby obtain more perfect and uniform penetration throughout that part of the pole required to be impregnated with the preservative.

40 In practice, I have found it necessary, in order to effect good results, to immerse the poles to a depth about one-fifth greater than the length of that part of the pole which it 45 is desired to impregnate. A pole thirty feet long, say, and required to be impregnated at its butt for a distance of six and one-half feet should have the butt immersed about from seven and one-half to seven and three-fourths feet.

50 After the air and moisture have been sufficiently expelled or extracted, which requires about six hours immersion for the average run of air seasoned timber, I continue to maintain the temperature of the preservative as nearly stationary as possible (235° F. to 240° F.) and then proceed to draw off the preservative liquid slowly from the treating tank thus gradually exposing 55 the upper part of the submerged portion of the pole to atmospheric temperature, whereby the rarefied vapors and air in the cavities of the wood begin to contract and form a 60 partial vacuum within the pole which causes 65 the preservative liquid to rise through the

bottom of the pole. The preservative is gradually drawn off from the treating tank and the pole gradually cools from the upper point of the submersion downward so that the bottoms of the poles are all the while 70 sealed against the entrance of air throughout the treating process and thus no cold liquid reaches the bottom of the poles, whereby viscosity of the liquid is not so raised as to clog or seal the pores.

75 The advantage of gradually drawing off the liquid while the temperature of the liquid is held at an elevated degree of heat is three-fold. (1) The viscosity of the preservative liquid is kept in the most favorable condition 80 for easy penetration through the cavities of the wood fiber. (2) At no time can air enter and take the place of the penetration of the preservative since the butts of the poles are sealed by hot preservative to the end of the 85 impregnating period of the poles. (3) The vacuum is formed gradually in the wood, from the upper point to which the poles have 90 been submerged, downward to the bottom as the hot preservative is slowly drawn from the treating tank. This mode of creating the vacuum gives a uniformity of action to the forces distributing the liquid and also lends time for more even penetration through the 95 more minute capillary voids in the wood. In other words, the conditions are such that the capillary pores take up the liquid by capillary attraction. It is impossible under any method known to me to force the liquid 100 into such capillary pores as contradistinguished from the visible or ordinary pores or cavities.

105 The time required for drawing off the oil depends upon the temperature of the surrounding atmosphere, the time being shorter in cool weather than in hot weather. The range of time will vary from four to eight hours, depending largely upon atmospheric temperature and conditions.

In brief, the invention may be summarized 110 as follows:

(1) Heating the preservative liquid to a temperature that will exclude absorption of the liquid by the poles when first immersed in the liquid, for the reason that the gases 115 and moisture in the wood will be expanded with sufficient force to prevent the preservative from entering the capillary cavities in the wood.

(2) The preservative is kept at a stationary or constantly rising temperature during the period of driving out the air and moisture,—so that little or no absorption of the liquid takes place in the poles during this 120 initial period of the treating process.

(3) The poles are heated to a greater depth than the space required to be treated, in order 125 to obtain a more perfect expulsion of air and moisture thereby producing a better vacuum 130

by which more desirable impregnation is obtained.

(4) The preservative, while still hot, is drawn off gradually, thus producing a vacuum slowly so that the preservative is gradually and evenly absorbed, and not rushed, at any point, as is the case when hot liquid is rapidly withdrawn.

(5) The preservative is kept in a very limpid state (at its low point of viscosity) so as to offer least resistance to penetration during the time of impregnation of the fiber of the timber.

(6) The bottoms of the poles are sealed against air by the hot preservative throughout the impregnating period so that there is no chance for air to enter the wood and interfere with the treating process while it is in operation.

20 From the foregoing description it will be seen that the timber is in no way injured, that no holes are formed therein seeking to allow the impregnating material to pass into the body of the wood, and furthermore, no large vats or receivers are necessary to carry out my process.

It will also be seen that no pressure, other than atmospheric pressure, is employed in carrying out the process, hence no expensive apparatus is needful.

It will, of course, be appreciated that in so far as the generic invention is concerned that instead of lowering the preservative in the tank or vat in which the pole or timber is placed, that the pole or timber may be gradually raised and thus the same effect produced as if the level of the liquid were gradually lowered. The claims, therefore, where they employ the phrase "securing a relative and gradual withdrawal of the bath with reference to the timber" are to be so interpreted as to cover either the lowering of the level of the bath or the gradual raising of the timber out of the bath.

45 Various forms of apparatus may be employed for carrying out the method above set forth but it is not deemed essential to an understanding of the invention to illustrate the same.

50 What is claimed is:

1. The process of impregnating timber which consists in immersing the same, in part at least, in a bath of liquid impregnating material raised to a temperature sufficiently high to cause such an expansion of the vapors and moisture content of the timber as to preclude the entrance of the impregnating material into the timber; maintaining the temperature of the bath; and finally securing a relative and gradual withdrawal of the bath with reference to the timber.

2. The process of impregnating timber which consists in immersing the same in a bath of liquid impregnating material raised

to a temperature approximating 212° F.; allowing the timber to remain therein for an appreciable period of time; and finally securing a relative and gradual withdrawal of the bath with reference to the timber while still maintaining the temperature of the bath.

3. The process of impregnating the butt of a pole which consists in immersing the butt in a bath of impregnating liquid maintained at a high temperature; allowing the butt to remain in the liquid for an appreciable time interval; and finally gradually withdrawing the bath from the butt while still maintaining the bath at a high temperature.

4. The process of impregnating the butt of a pole which consists in immersing the butt in a bath of hot liquid impregnating material, the depth of immersion being somewhat in excess of the extent to which impregnation is desired in the butt; retaining the hot liquid about the butt for an appreciable time interval; and finally gradually lowering the bath about the pole.

5. The process of impregnating the butt of a pole which consists in heating the butt by immersing it in a bath of heated impregnating material and thereby producing a partial vacuum in the cavities and pores in the butt by the expansion and expulsion of the contained gases and moisture content; and finally gradually lowering the bath about the butt while still maintaining the bath in its heated condition whereby the butt will be progressively cooled toward the immersed end and such cooling will effect a contraction of the gases remaining in the butt and a consequent indrawing of the impregnating material into the butt.

In testimony whereof I have signed my name to this specification.
